UNITED STATES PATENT OFFICE.

AXEL A. STROM, OF AUSTIN, ILLINOIS, ASSIGNOR TO THE WALMSLEY & COMPANY, OF CHICAGO, ILLINOIS.

DESIGN FOR A GAS-BURNER.

SPECIFICATION forming part of Design No. 30,901, dated May 30, 1899.

Application filed March 10, 1899. Serial No. 708,608. Term of patent 14 years.

To all whom it may concern:

Be it known that I, AXEL A. STROM, a citizen of the United States, residing at Austin, in the county of Cook and State of Illinois, have invented and produced a new and original Design for a Gas-Burner, of which the following is a specification.

The accompanying drawing shows my design of a gas-burner by a perspective view.

As shown in the accompanying drawing, the leading or material feature of my design consists in the diverging branch arms A A on the end of the burner-tube B, terminating in tips C C, having the gas-discharge openings a a in their opposing faces.

The tips C C, which are shown of square shape, form heads on the ends of the diverging branch tubes and extend at their angles of inclination with reference to the burner-tube.

Having described my invention, what I claim as new, and desire to secure by Letters Patent, is—

The design for a gas-burner, as herein shown and described.

AXEL A. STROM.

In presence of—

M. J. FROST,
R. T. SPENCER.
